UNITED STATES PATENT OFFICE.

WILLIAM L. PAUL, OF BERKELEY, CALIFORNIA, ASSIGNOR TO DEERE AND COMPANY,
OF MOLINE, ILLINOIS, A CORPORATION OF ILLINOIS.

CULTIVATOR.

1,335,074.

Specification of Letters Patent. Patented Mar. 30, 1920.

Application filed April 25, 1916. Serial No. 93,404.

To all whom it may concern:

Be it known that I, WILLIAM L. PAUL, a citizen of the United States, residing at Berkeley, in the county of Alameda and State of California, have invented certain new and useful Improvements in Cultivators, of which the following is a specification, reference being had therein to the accompanying drawing.

10 My invention relates to cultivators, more particularly of the two-row type, and has for its object the construction and operation of certain mechanism by which the direction of travel of the machine can be controlled to suit varying conditions of cultivation; also to means by which the gangs of cultivating devices can be adjusted laterally or lifted out of an operative position.

20 Referring to the drawings in which similar numerals indicate identical parts—

Figure 1 is a plan view of a two row cultivator embodying my invention.

Fig. 2 is an end elevation of Fig. 1 with 25 the wheels removed.

Fig. 3 is an enlarged detail of the gang shifting mechanism, and

Fig. 4 is a rear view of one end of the cultivator.

30 The main frame consists of a front bar 1 and a rear bar 2 bent at their ends and secured together by castings 3 securely bolted thereto. Preferably integral with the castings 3 are vertical bearings 4 in which 35 are journaled spindle ends of crank axles 5 which extend rearwardly of the main frame and have their terminations bent laterally to form stub axles on which are supporting wheels 6. A seat support, having a seat 7

40 on the rear end thereof, comprises parallel bars 8 and 9 spaced apart and pivotally supported on the frame in the following manner: Midway the length of the frame bar 1 is securely bolted a bracket 10 having

45 rearwardly extending parallel arms 11 and 12; braces 13 and 14 are secured to the bars 8 and 9 respectively and project forwardly and upwardly, beneath the arm 11, supporting a casting 15; a V-shaped brace 16 is 50 riveted to the frame bar 2 and extends forwardly its angle overlapping the arm 11; a king bolt 17 is inserted through suitable openings in the brace 16 the arm 11, the casting 15 and the arm 12, and projects be-

low the latter to receive a casting 18 to 55 which the forward ends of the seat bars 8 and 9 are secured; the castings 15 and 18 are free to turn on the king bolt 17 so that the seat support can be swung laterally in either direction toward the wheels 6, the 60 castings 15 and 18 being held against downward movement on the king bolt 17 by pins or cotters 19.

Rigidly secured between the seat support bars 8 and 9 is a member 20 having a vertical stud or pin 21 on which is loosely mounted a sleeve 22 having preferably integral therewith a horizontal sleeve 23; secured midway its length in the sleeve 23 is a rod 24 having its ends hooked to engage with 70 the rearward ends of arms 25 rigidly mounted on the upper ends of the spindles.

The rigs of cultivating devices are arranged in pairs and comprise bars 26 and 27 secured together at their rear ends, and 75 connected at their forward ends to couplings 28 having sleeves 29 which are mounted on the horizontal ends of yokes 30. Between the sleeves 29 on each of the ends of the yokes 30 are collars 31 having eyes 32; 80 braces 33 are pivotally secured to the frame bar 2 and extend forwardly and downwardly toward the eyes 32; braces 34 are pivotally mounted on the frame bar 1 and have eyes in their lower ends which register 85 with the eyes 32, through the eyes on the braces 34 and the lower ends of the braces 33 extend and are secured in place by cotters or pins as may be desired. The yokes 30 are vertically disposed, their upper horizontal portions 35 being loosely held in guides 36 secured to the frame bar 1. On the inner vertical portions of the yokes 30 are clips 37 to which are connected links 38 and 38^a extending toward the center of the 95 cultivator.

Secured between the bars 8 and 9 of the seat support, and preferably central of the main frame, is a member 39 having a downwardly extending spindle 40 on which is 100 pivotally mounted bell cranks 41 and 42 so that their lateral arms 43 extend in opposite directions, and their forwardly extending arms 44 are parallel, the forward end of the arm 44 of the bell crank 41 being pivotally 110 connected to the link 38, and the end of the arm 44 of the bell crank 42 pivotally connected to the link 38^a.

Pivots mounted intermediate its ends on the seat support is a manually operable lever 45 provided with the usual type of latch to engage with notches in a rack bar 46 secured on the seat support. To the lower end of the lever 45 is connected a rod 47 which extends forwardly and is hooked to the arm 43 of the bell crank 42, and a similar rod 48 connects the lever 45 with the 10 arm 43 of the bell crank 41. By the construction just described it will be seen that the yokes 35 and connected cultivating rigs can be adjusted toward or from each other by operating the lever 45, the latter actuating the bell cranks 41 and 42 so that the 15 yokes 35 are adjusted toward or from each other through the links 38^a which are connected thereto and to the bell cranks 41 and 42, the yokes having a swinging movement 20 on the braces 33 and 34, pivoted on the main frame and by which the yokes 35 are supported.

The cultivating rigs are raised independently or simultaneously, as may be desired, 25 in the following manner; journaled in suitable bearings on the frame bar 2, and adjacent the ends of the main frame, are rock shafts 49 and 50 having on their outer ends forwardly extending arms 51 which are connected to links 52, the latter connected at their lower ends to the outer cultivating rigs. The inner ends of the rock shafts 49 and 50 have arms 53 on which are rigidly mounted hand levers 54. Between the rock shafts 49 30 and 50 and in alinement therewith and journaled in suitable bearings on the frame bar 2, is a rock shaft 55 on one end of which is a master lever 56 provided with the usual form of latch to engage with notches in a 35 segmental rack 57 mounted on the main frame; loosely mounted on the rock shaft 55 near the ends thereof, are levers 58 provided with forwardly extending arms 59 to which are connected links 60 having their 40 lower ends attached to the inner cultivating rigs. Secured to the master lever 56 and on one side thereof a segment 61 having notches with which a latch on the lever 54 engages, and secured to the opposite side of the master lever 56 is a similar segment 62 having 45 notches with which a latch on the adjacent lever 58 engages.

At the opposite end of the rock shaft 55 and mounted thereon are segments 63 and 64, 50 the adjacent lever 58 having a latch of the usual type to engage with notches on the segment 63, and the lever 54 having a similar latch to engage with notches in the segment 64. By the mechanism just described it is 55 apparent that each cultivating rig can be raised at will, independently of the others, by actuating the lever to which it is connected and if it is desired to raise all the rigs simultaneously it can be readily done by 60 means of the master lever 56. The rigs are

maintained in parallel relation by means of yokes 65 which are pivotally connected to the links 52 and 60 of each pair of rigs.

In adjusting the wheels angularly the operator with his feet upon the treadles 66 on the inner rigs swings the seat support on its pivot 17 in the desired direction, and as the rod 24 is connected to the seat support and to the arms 25 on the spindles of the crank axles 5 they are moved simultaneously in the 70 same direction, angling the wheels and at the same time moving the frame and connected rigs in the same direction; it will be noted in this connection that the pivot 17 and the pivotal connections of the links 38 75 and 38^a with the bell crank arms 44 are in a direct vertical line, consequently any lateral movement of the frame, when the wheels are angularly adjusted, will not disturb the position of the rigs as it was prior 80 to such adjustment, and for the same reason the rigs can be adjusted independently or simultaneously at any time.

What I claim is—

1. In a cultivator having a frame, axles 90 having vertical spindles journaled on the frame, said axles extending rearwardly of the frame and having wheels on the rearward ends, a seat support mounted on the frame to swing laterally, gangs of cultivating devices supported on the frame, horizontally disposed arms rigidly mounted on said spindles and extending parallel to each other, means connecting said arms and seat support whereby as the seat support is swung 95 laterally said spindles are rotated to angle the wheels relatively to the frame and gangs of cultivating devices moving simultaneously in the same direction, and means to move said gangs laterally independent of the movement of the frame.

2. In a cultivator having a frame, axles 100 having vertical spindles journaled on the frame, said axles extending rearwardly of the frame and having wheels on the rearward ends, a seat support pivotally mounted on the frame to swing laterally, gangs of cultivating devices supported on the frame, means connecting said seat support and spindles to actuate the latter by swinging 105 the seat support to adjust the wheels angularly to the frame, the frame and gangs of cultivating devices moving simultaneously in the same direction, and means to move said gangs laterally independent of the 110 movement of the frame.

3. In a cultivator having a frame, axles 115 having vertical spindles journaled on the frame, said axles extending rearwardly of the frame and having wheels on the rearward ends, a seat support pivotally mounted on the frame to swing laterally, gangs of cultivating devices supported on the frame, means connecting said seat support and spindles to actuate the latter by swinging the 120 125 130

seat support to adjust the wheels angularly to the frame, the frame and gangs of cultivating devices moving simultaneously in the same direction, and means on the seat support operable to move said gangs laterally independent of the movement of the frame.

In testimony whereof I affix my signature in presence of two witnesses.

WILLIAM L. PAUL.
